Fig. 3.

Fig. 4.

Fig. 5.

Fig. 6.

FIG. 1 is an isometric view of a carrying case showing my new design and illustrating the top and one side and end thereof;

FIG. 2 is an isometric view thereof in lowered position and illustrating the bottom, and the opposite side and end shown in FIG. 1 and the carrying strap in extended position;

FIG. 3 is a bottom plan view of the carrying case shown in FIG. 1;

FIG. 4 is an isometric view of the case shown in FIG. 1 in an open position, illustrating the flanged sides of the hinged cover which fit inside the waffled end pieces, the carrying strap being extended;

FIG. 5 is an isometric view of another embodiment of the carrying case shown in FIG. 1, wherein the side edges of the hinged cover are rolled, so that the cover will overlie the waffled end pieces and complete the framed effect thereof;

FIG. 6 is an isometric view of the case shown in FIG. 5 and illustrating the bottom and the opposite side and the carrying strap in extended position;

FIG. 7 is a bottom plan view of the case shown in FIG. 5; and

FIG. 8 is an isometric view of the case shown in FIG.

5, and illustrating said case in open position and the carrying strap in extended position.

In FIGS. 2, 4, 6 and 8 portions are broken away for convenience of illustration only.

The essential features of my design reside in an adjustable recessed mounted carrying strap in combination with the treatment of the case walls, wherein a pair of opposed case walls have pluralities of projections in relief thereon and another of said case walls is provided with a hinged panel extended transversely of the case.

I claim:

The ornamental design for a carrying case, as shown and described.
